(57) CLAIM

The ornamental design for a bib, as shown and described.

DESCRIPTION

FIG. 1 is a perspective view of a bib showing my new design in use;

FIG. 2 is a further perspective view thereof;

FIG. 3 is a front elevational view thereof; the opposite side being a mirror image thereof;

FIG. 4 is a right side elevational view thereof; the opposite side being a mirror image thereof;

FIG. 5 is a perspective view thereof with a top portion being folded over; and,

FIG. 6 is a front elevational view thereof with slits being shown partially opened.

The broken line showings form no part of the claimed design.
